Patented July 7, 1914.

UNITED STATES PATENT OFFICE.

RODERICK G. COLLINS, JR., OF NEW YORK, N. Y.

TERMINAL FOR PNEUMATIC-DESPATCH APPARATUS.

1,102,324.

Specification of Letters Patent.

Patented July 7, 1914.

Application filed April 28, 1913. Serial No. 764,139.

To all whom it may concern:

Be it known that I, RODERICK G. COLLINS, Jr., a citizen of the United States, residing at New York city, in the county of New York and State of New York, have invented new and useful Improvements in Terminals for Pneumatic-Despatch Apparatus, of which the following is a specification:

This invention relates to an improvement 10 in terminals for pneumatic despatch tube apparatus, and has for its purpose the simplification of the manner of stopping the car in the terminal of the tube so that it will not pass therefrom with such velocity or momentum that it might cause damage or injury to other cars then upon the receiving table, or possibly to employees. As the invention relates only to this part of the pneumatic tube despatch apparatus, only so much thereof 15 20 25 30 35 40 45 50 55 60 65 70 75 80 85 90 95 100 105 110

The invention resides in the terminal hereinafter described. That which is new is set forth in the claims appended to the description.

In the accompanying drawings—Figure 1 is a longitudinal sectional view of a terminal embodying this invention. Fig. 2 is a cross sectional view. Fig. 3 is a view similar to Fig. 1 showing the movable section adjusted radially outward to permit passage of the carrier. Fig. 4 is a detail showing an arrangement of air cut-off gate.

In the said drawing, the reference numeral 1 designates the terminal of a pneumatic despatch tube within which it is designed that the carriers shall come to rest, as before explained. The interior of the wall of this tube converges toward the exit end, providing a passage of gradually reduced dimensions to constitute a mechanical 50 brake for the carrier, the wheels whereof engage the radially rigid converging wall until movement of the carrier is arrested. The convergence or taper of the wall is very gradual and relatively slight so that the 55 movement of the car is gradually checked

until it comes to a full stop. It is sufficient for the purposes of the invention that a segment only of the interior of the wall of the tube taper. Preferably, as shown in the drawings, a plurality of arcs or segments of the wall taper; as shown at 2 and 3 of the drawings two sections taper. In Figs. 1 and 2 these segments which produce the convergence of the carrier-passage through the tube are diametrically opposite, one segment being movable and the other fixed or stationary. It is essential after the car shall have come to rest as described that a passage therefor shall be provided that it may be ejected from the tube onto the receiving table, and for this purpose at least one of the segments or arcs of the wall is made movable. As shown, the segment or arc 2 at the base of the terminal is so made movable. In Figs. 1 and 2 of the drawing the parts are shown in normal position, for arresting the movement of the carrier, and in Fig. 3 in position to permit the passage of the carrier from the terminal, or, when the terminal is used as a sending terminal, to permit entrance of the carrier to and passage through the terminal. In the preferred embodiment of the invention shown in the drawings the movable section is pivoted at one end to the tube, as at 4, is free at the other end and works in a well or enlargement 5 of the terminal 1, within which is disposed suitable means for elevating and rigidly holding the movable section or sections into position to arrest a carrier and to allow said sections to assume normal position for passage of the carrier. As shown, this mechanism consists of a cam roll 6 arranged within the well or enlargement 5 in co-operative relation with the free end of the movable section.

As shown in the drawings, Fig. 2, the movable section is provided with a runway 7 intended to accommodate the vertical traction wheel of a carrier, where the carrier is provided with such, as in the dotted line illustration. The runway, when necessary by reason of the nature of the carrier, will be sufficiently wide to insure alinement with said traction wheel of the carrier. So far as observed by me in connection with carriers provided with traction wheels, as is illustrated in my companion application for Letters Patent executed of even date and filed concurrently herewith, the line of

travel of said traction wheel does not deviate more than a fraction of an inch, and, therefore, a runway which has one inch clearance will be sufficient.

5 To guard against the possibility of shock as the carrier engages the converging wall passage, the terminal is so combined with the transmitting tube 9 that it will yield slightly under pressure of the carrier. One 10 means by which this may be accomplished is shown in the drawings, Fig. 1, wherein the terminal has yielding connection with the despatching tube by means of a series of bolts or the like 10 engaging flanges 11 with 15 which the terminal and tube are provided, and combined with the said bolts and held in operative connection therewith by means of nuts or the like 12 are springs of sufficient tension to normally hold the terminal in 20 close contact with the tube as shown, but which will yield as the carrier meets the converging wall of the tube. Very slight yield of the terminal is sufficient for this purpose.

To preserve the proper relative position 25 of the terminal with relation to the tube and the carriers passing therethrough, that is to say so that when the movable section of the terminal is provided with a runway 7, the latter may be in position to receive the traction wheel of the carrier, suitable guides are provided such, for example, as shown in the drawing wherein 13 designates an annular flange of the terminal fitting into a corresponding recess 14 in the end of the tube, and, obviously, the connection may be suitably packed to be air tight. The discharge 30 end of the terminal is provided with a gate 15 which, preferably, and as shown, is arranged to be manually opened and closed, 35 and the purpose of which is to confine the air when the terminal is to be used as a blast despatch terminal.

I prefer, although this is not essential in 40 respect of the broader character of the invention, to provide in connection with the movable section of the terminal tube a positive stop or guard, one suitable arrangement of which consists of a dog 16, the head of which is pivotally disposed in an opening 17 at the 45 free end of the movable section and the tail of which rides through and bears against the wall of a guide 18, so that when the free end of the section is moved to restrict the carrier passage and arrest the carrier in the 50 tube, the nose of this dog will be projected inwardly beyond the plane of the surface of the movable section into the path of the carrier and positively arrest movement of the 55 same. This positive stop may be utilized with safety as when the carrier shall have arrived at the same, if it have any movement it will be so slight that no appreciable shock 60 will result by absolute positive stoppage thereof. Conversely, when the movable sec-

tion is moved to normal position for passage 65 of the carrier the nose of the dog will automatically withdraw into a plane flush with the surface of the movable section.

The movable section may be suitably operated manually, and to this the invention 70 is not restricted, one suitable way being by means of a sufficiently weighted arm 20 connected to the shaft 21 of the cam roll 6, which weighted arm maintains, through the cam roll, the movable section in the normal 75 position illustrated in Figs. 1 and 2, and returns the same after the operation of discharging a carrier from the terminal or introducing one thereinto when the terminal is used as a sending terminal.

The present invention does not relate to the manner of ejecting the carrier from the terminal nor for despatching the same through the terminal into the transmitting tube 9, and any suitable means may be employed to perform these functions, and one means is shown in my before-mentioned application Serial No. 737523, which is herein conventionally shown.

a designates a gate arranged in the terminal and which may be closed after the carrier has come to rest.

b designates a compressed air conduit from a tank *c* and communicating with the terminal intermediate the gate and the position of rest of the carrier, so that when it is desired to deliver the carrier from the terminal the gate *a* is closed, the gate 15 opened, the movable section of the terminal wall adjusted to the position illustrated in 100 Fig. 3 of the drawing, and the valve *d* opened to admit pressure to the terminal for moving the carrier from the terminal onto a suitable receiving table not shown.

When the terminal is used as a despatching terminal by blast, the conduit *c* has a branch *c'* near the receiving end of the terminal controlled by a valve *e*, so that pressure may be introduced behind the carrier to transport the latter through the terminal to the despatching tube 9 where it is taken care of by suitable despatching apparatus.

Having thus described my invention, what is claimed is:—

1. A terminal for pneumatic despatch apparatus yieldingly connected to the despatch tube and having a converging or restricted radially rigid interior for arresting movement of a carrier.

2. A terminal for pneumatic despatch apparatus longitudinally yieldingly connected to the despatch tube and having a gradually converging or restricted interior for arresting movement of a carrier.

3. A terminal for pneumatic despatch apparatus yieldingly connected to the despatch tube and provided with a movable section arranged to be projected into the path of a

carrier for arresting the latter, and means for rigidly holding said section in such position.

4. A terminal for pneumatic despatch apparatus yieldingly connected to the despatch tube and provided with a section pivoted at one end and the other end free to be projected into the path of a carrier for arresting the latter, and means for rigidly holding 10 said section in such position.

5. In combination with the despatch tube of a pneumatic despatch apparatus, a terminal longitudinally yieldingly connected to said tube and the wall of which is provided with 15 a section pivoted at one end and the other end of which is free to be projected into the path of a carrier for arresting the latter, and means for rigidly holding said section in such position.

20 6. A terminal for pneumatic despatch apparatus provided with a section pivoted at one end and the other end free to be projected into the path of a carrier for arresting the latter, and an auxiliary stop coöperatively combined with and operated by 25 said movable section.

7. In combination with the despatch tube of a pneumatic despatch apparatus, a terminal yieldingly connected thereto and the 30 wall of which is provided with a section pivoted at one end and free at its other end to be projected into the path of a carrier for arresting the latter, and an auxiliary stop coöperatively combined with and operated 35 by said movable section.

8. A terminal for pneumatic despatch apparatus provided with a section pivoted at one end and the other end free to be projected into the path of a carrier for arresting the latter, a dog pivotally carried by 40 said movable section, and means for projecting the nose of said dog inwardly beyond the plane of the surface of the movable section when the latter is moved inwardly and for also disposing said nose of the dog flush 45 with the surface of said section when the latter is moved outwardly.

9. In combination with the despatch tube of a pneumatic despatch apparatus, a terminal tube yieldingly connected therewith 50 and provided with a section pivoted at one end and the other end free to be projected into the path of a carrier for arresting the latter, a dog pivotally carried by said movable section, and means for projecting the 55 nose of said dog inwardly beyond the plane of the surface of the movable section when the latter is moved inwardly and for also disposing said nose of the dog flush with the surface of said section when the latter is 60 moved outwardly.

In testimony whereof I have hereunto set my hand in presence of two subscribing witnesses.
